UNITED STATES PATENT OFFICE.

PIERRE L. FRAILEY, OF CLEVELAND, OHIO.

DESIGN FOR A BOTTLE.

Application filed December 30, 1927. Serial No. 24,700. Term of patent 14 years.

To all whom it may concern:

Be it known that I, PIERRE L. FRAILEY, a citizen of the United States, residing at Cleveland, in the county of Cuyahoga and State of Ohio, have invented a new, original, and ornamental Design for a Bottle, as shown in the accompanying drawing, forming part of this specification.

In said drawing:—

Fig. 1 is a perspective view of the front side of the bottle.

Fig. 2 is a perspective view of the back side of the bottle.

Fig. 3 is a top plan view of the bottle.

The essential or dominant features of the design are the vertical flutings, and the indented spaces on the front face of the bottle, substantially as shown.

I claim:

The ornamental design for a bottle substantially as shown and described.

PIERRE L. FRAILEY.
